UNITED STATES PATENT OFFICE.

CHARLES R. DE BEVOISE, OF NEWARK, NEW JERSEY.

APPAREL.

No. 852,262.

Specification of Letters Patent.

Patented April 30, 1907.

Application filed June 7, 1906. Serial No. 320,671.

To all whom it may concern:

Be it known that I, CHARLES R. DE BEVOISE, a citizen of the United States, residing at Newark, in the county of Essex and State 5 of New Jersey, have invented new and useful Improvements in Apparel, of which the following is a specification.

This invention relates to a bodice having pants or drawers combined therewith.

10 This invention resides in the novel features of construction set forth in the following specification and claim and illustrated in the annexed drawing, in which:

Figure 1 is an inside view of a garment embodying this invention. Fig. 2 is a section along *xx* Fig. 1.

This garment or apparel comprises a bodice or body portion *a* and a lower portion *b* forming a pair of drawers or pants. The upper and lower portions are sewed or secured together to be permanently connected. The bodice opens at the back. Such bodice is suitably boned or provided with steels *c*. The closed front of such bodice will cause a 25 neat appearance or fit to be secured when worn as an undergarment. The bodice is shown composed of pieces united by seams which can be designated as an upper bust seam *d*, a bias gore seam *e* and a vertical gore seam *f*. The word vertical of course is not necessarily limited to mathematically perpendicular but refers to a seam extending downwardly along the garments as indicated. A bodice cut and made up as indicated 30 enables the body and pants portions to be sewed together so as to fit the wearer smoothly or without Shirring, puckering or wrinkling. When worn with an outer garment such apparel or undergarment will not 35 cause any fold or irregularity which spoils the contour or interferes with the fit of the dress or any portion thereof.

A tab is shown at *g*. This tab is placed at the lower inner portion of the bodice. Such 40 apparel when combined with a fastening tab

can be connected to the corset so as to be kept in fit and sitting closely to or on the figure. The tab is adapted to hook to the post on the corset clasp. Eyelets are placed at suitable points along the tab. 50

The lower edge of the body portion is cut or curved so as to fit or sit neatly about the waist when the apparel is put on. The drawers portion has each leg sewed or secured by a seam running unbrokenly about the 55 waist line. The front of the body part is permanently closed so that no joint or line of buttons will interfere with a neat fit of the outer garment over the bust. The rear portions of the body part extend beyond the drawers or 60 leg parts so that as the garment is put on and the rear parts of the body are overlapped as the bodice is drawn tight the drawer portions will not be caused to overlap or crease one another. 65

I claim:

1. A bodice having an entirely closed front and provided with bone stays, leg portions secured to the bodice and depending therefrom, and a tab interposed between the leg 70 portions and secured and depending from said bodice and having a series of eyelets, said bodice being extended at opposite sides beyond the leg portions to close said bodice at the rear thereof. 75

2. A bodice having a closed front and separate legs fastened to the lower edge of the bodice, the rear portions of the bodice being free of the legs and extending rearwardly beyond the latter, the bodice having a pendent 80 flap or tab between the legs for connection with a corset.

In testimony whereof I have hereunto set my hand in the presence of two subscribing witnesses.

CHARLES R. DE BEVOISE.
